DESIGN FOR A BICYCLE FRAME OR THE LIKE

Charles J. Fogarty, Westfield, Mass., assignor to
Edward H. Broadwell, receiver of Westfield
Manufacturing Company, Westfield, Mass., a
corporation of Massachusetts

Application August 7, 1933. Serial No. 48,949

Term of patent 14 years

To all whom it may concern:

Be it known that I, CHARLES J. FOGARTY, a citizen of the United States, residing at Westfield, in the county of Hampden, and State of Massachusetts, have invented a new, original, and ornamental Design for a Bicycle Frame or the Like, of which the following is a specification, reference being had to the accompanying drawing, forming a part thereof.

The figure is a side elevation of a bicycle frame showing my new design, the opposite side presenting substantially the same appearance as that of the side shown.

I claim:

The ornamental design for a bicycle frame or the like as shown and described.

CHARLES J. FOGARTY.
